UNITED STATES PATENT OFFICE.

CHARLES A. UTZ, OF ROCHESTER, NEW YORK.

STATION-INDICATOR.

No. 852,475.

Specification of Letters Patent.

Patented May 7, 1907.

Application filed November 1, 1906. Serial No. 341,653.

To all whom it may concern:

Be it known that I, CHARLES A. UTZ, a citizen of the United States, residing at Rochester, in the county of Monroe and State of New York, have invented certain new and useful Improvements in Station-Indicators, of which the following is a specification, reference being had therein to the accompanying drawing.

This invention relates to improvements in street or station indicators for use on street cars, railway cars, and the like.

The object of the invention is to provide a simple, practical and efficient device of this character which may be readily operated by the conductor or motorman of a car to indicate the streets or stations as they are approached.

Further objects and advantages of my invention, as well as the structural features by means of which they are attained, will be made clear by an examination of the specification, taken in connection with the accompanying drawings, in which the same reference numerals indicate corresponding portions throughout, and in which,

Figure 1 is a perspective view of the improved indicator; Fig. 2 is a front elevation with the front of the casing removed; Fig. 3 is a side elevation with the side of the casing removed, the pawl and ratchet feed mechanism for the indicator apron being shown in its normal position in full lines and in its actuated position in dotted lines; Fig. 4 is a vertical sectional view, parts being broken away to show the spring-pressed bearing for the tension roller of the indicator apron; and Figs. 5 and 6 are detail perspective views of one of the pawls or dogs and of the lever which carries them.

Referring to the drawings by numeral, 1 denotes the outer casing or covering of the improved street or station indicator for cars, or the like. This casing may be of any desired form and construction, and may be suitably secured at one end or any other convenient part of a car. As shown, the casing is rectangular in form and has in its front a sight opening 2 covered by glass so that the names of the streets or stations upon an indicator apron 3 may be seen. This apron has its ends secured to and wound in opposite directions upon upper and lower rollers 4, 5 which have their shafts 6, 7 journaled in two similar side plates 8 of a frame suitably mounted within the casing 1. Said plates

are connected at the rear by bars 9 which have their ends seated in dove-tailed recesses in the plates. The apron is adapted to be wound upon one of the rollers as it is unwound from the other, and said rollers are caused to move together by a pair of meshing gears 10 fixed upon the adjacent ends of their shafts. The apron or belt 3 also passes over a tension roller 11 which takes up all slack and holds the stretch of the apron passing across the sight opening 2, substantially vertical. This tension roller has its journals mounted in bearing blocks 12 which slide in guides 13 formed in the side plates 8 and which are forced outwardly by springs 14, as clearly shown in Fig. 4.

One end of the shaft 7 of the lower winding roller or drum 5 is extended through the adjacent side of the casing 1 and carries a knob 75 or handle 15 by means of which the rollers may be turned in either direction to set the apron so that the desired name appears in the sight opening 2. The apron is also actuated in either direction by pulling upon cords 80 or other flexible elements 16 attached to the upper arm 17 of a bell-crank 18. The latter is pivoted upon a stud 19 projecting from one of the plates 8 and has its arm 17 projecting through a slot in the top of the casing 1. The other two arms 20 of the bell-crank are connected by cords or similar flexible connections 21 to two projections or arms 22 provided upon dogs or pawls 23, 24, which latter coact with a ratchet-wheel 25 secured upon 90 the shaft 7. These pawls are pivoted at 26 upon the opposite ends of a lever 27 which is in turn pivoted at its center upon the shaft 7 between the wheel 25 and the adjacent side plate 8. The projecting arms 22 are secured to the pawls by set-screws 28 and they carry inwardly-projecting pins or studs 29 which enter arc-shaped slots or recesses 30 formed in the lever 27. The provision of these pins and slots limits the movement of 100 the pawls. The pawls are held normally out of engagement with the ratchet-wheel by springs 31 secured at one of their ends to studs upon the lever 27 and having their other free ends engaged with the screws 28. 105 The lever 27 is held normally in its horizontal position by two leaf-springs 32 which may be formed integral, if desired. These springs, as shown in Fig. 3, are secured to a block or projection 33 arranged upon one of the side plates 8, and their free ends 34 bear upon the upper edges of the ends of the lever 27. The

swinging movement of the latter is limited by two stop pins 35 projecting from the adjacent plate 8 and adapted to be engaged by the pawls.

5 In order to notify the passengers of the car each time the device is actuated, I preferably arrange upon one of the plates 8 a bell 36 and provide hammers 37 for the same upon the arm 17 of the bell-crank 18. It will be seen, 10 upon reference to Fig. 3, that when the lever or bell-crank 18 is moved in either direction, the hammer 37 will strike and sound the bell 36.

In operation, one or the other of the cords 15 16 is pulled by the conductor or motorman after the car passes each street or station, so that the apron is moved in the proper direction to cause the names of the streets or stations along the route of the car to successively appear in the sight opening of the casing. When one of the cords 16 is pulled the bell-crank 18 is rocked so that one of its lower arms 20 is elevated. This movement of the arm 20 swings the pawl to which it is 25 connected into engagement with the ratchet-wheel and the continued upward movement of the arm 20 then causes the winding rollers to be turned sufficiently to bring the name of the next street or station before the sight 30 opening 2. The oscillation of the lever 27 is limited by the stops 35 so that the apron is prevented from turning too far. The provision of the tension roller prevents any slack in the apron. The spring or springs 32 hold 35 the lever 27 normally horizontal and hence

the pawls out of engagement with the ratchet-wheel, so that by properly turning the knob 15 the apron may be set as desired.

Having thus described my said invention, what I claim as new and desire to secure by 40 Letters Patent of the United States, is

In a device of the character described, a casing having a sight opening and a slot, winding rollers within said casing, an indicator apron upon said rollers adapted to travel 45 across said sight opening, meshing gears upon the shafts of said rollers, a ratchet wheel upon the shaft of one of said rollers, a lever pivoted intermediate its ends upon the shaft carrying the ratchet wheel, pawls pivoted 50 upon the opposite ends of said lever and adapted to engage said ratchet wheel, springs for holding said pawls away from said ratchet wheel, means for limiting the swinging movement of said pawls, leaf springs engaging the 55 opposite ends of said lever for returning it to its normal position, a T-shaped bell crank, loose connections between the opposite arms of said bell crank and said pawls, the third arm of said bell crank being adapted to project through the slot in said casing, bell hammers upon the third arm of said bell crank, and a bell arranged in the path of said hammers.

In testimony whereof I hereunto affix my 60 signature in presence of two witnesses.

CHARLES A. UTZ.
